R. P. WRIGHT.
AUTOMATIC PRESSURE ROLL RELEASE FOR CLOTHES WRINGERS.
APPLICATION FILED OCT. 26, 1916.

1,220,044.

Patented Mar. 20, 1917.

UNITED STATES PATENT OFFICE.

REA P. WRIGHT, OF WASHINGTON, DISTRICT OF COLUMBIA, ASSIGNOR TO JOHN FRANCIS HEMENWAY, OF NEW YORK, N. Y.

AUTOMATIC PRESSURE-ROLL RELEASE FOR CLOTHES-WRINGERS.

1,220,044.

Specification of Letters Patent. Patented Mar. 20, 1917.

Application filed October 26, 1916. Serial No. 127,895.

To all whom it may concern:

Be it known that I, REA P. WRIGHT, a citizen of the United States, residing at Washington, in the District of Columbia, 5 have invented certain new and useful Improvements in Automatic Pressure-Roll Releases for Clothes-Wringers, of which the following is a specification, reference being had therein to the accompanying drawing.

10 This invention relates to certain new and useful improvements in an automatic pressure roll release for clothes wringers, and the object of the invention is to provide means for automatically releasing the pressure 15 on the pressure rolls instantaneously without allowing the top bar to become displaced from the wringer frame.

Another object of my invention is to provide a clothes wringer having movably 20 mounted retaining members coöperating with the movably mounted top bar in such a manner that the top bar can be held in predetermined position so that the proper pressure can be exerted on the pressure rolls 25 and allowed to move vertically in order to release said pressure means without becoming detached from the wringer frame.

Another and further object of the invention is to provide novel means for operating 30 the movably mounted members for holding the movably mounted top bar in position within the wringer frame which are in the form of an angular lever pivotally mounted on the wringer frame having portions ar- 35 ranged in the path of travel of one of the pressure roll shafts, and connected at the opposite ends to the movably mounted members so that when the pressure rolls are separated, the movable members will be shifted 40 in order to release the pressure on the pressure rolls.

Other and further objects and advantages of the invention will be hereinafter set forth and the novel features thereof defined by the 45 appended claims.

In the drawings,

Figure 1 is a side elevation partly in section of a clothes wringer showing the application of my improved construction of pressure roll releasing device thereto; and

Fig. 2 is an end elevation of the same.

Like numerals of reference refer to like parts in the several figures of the drawing.

In carrying out my invention, I employ a 55 wringer of the ordinary construction com-

posed of a frame 1 having slotted side bars in which are mounted superposed bearings carrying pressure roll shafts 2 and 3, the upper bearings having spring supports on which are mounted pressure springs 4 en- 60 gaged by bearing plates 5 carried by a pressure bar 6. The bearing plates 5 of the pressure bar 6 are adapted to be engaged by pressure screws 7 mounted in threaded boxes 8 of the movably mounted top bar 9 which 65 is slidably mounted within the slotted side bars of the wringer frame.

Secured across the slots of the side bars of the wringer frame at their upper ends are movably mounted retaining members 10 70 in the form of plates having guide slots 11 through which guide screws or pins 12 are adapted to pass for holding said plates in position on the wringer frame in such a manner that the plates are free to move 75 transversely. The plates are provided with notches 13 adapted to receive the projecting studs 14 carried by the ends of the movably mounted top bar 9 so as to allow the top bar to move vertically within the wringer frame 80 when the notches 13 are brought into vertical alinement with the studs 14, the lower edge of said plate being normally held in a plane above the studs 14 as shown in Fig. 2 so as to hold the movably mounted top 85 bar in predetermined position within the wringer frame in order to allow the pressure screws to be adjusted so that the desired pressure on the pressure rolls can be obtained. 90

In order to provide means for automatically shifting the retaining members 10 transversely of the wringer frame so as to bring the notches 13 thereof into vertical alinement with the studs 14 of the mov- 95 ably mounted top bar, I pivotally mount on the side bars of the wringer frame angular levers 15 which are slidably connected at 16 at their upper ends to the retaining members 10, and are provided with portions 17 at 100 their lower ends arranged in the path of travel of the pressure roll shaft 3 so that when the pressure roll shaft is moved by the separation of the pressure rolls, the portions 17 will be engaged by the pressure roll shaft 105 so as to rock the lever 15 on its pivot 18 which will move the retaining members 10 into such position that the top bar is allowed to move vertically a predetermined distance 110 in order to release the pressure means, but 115

is prevented from becoming detached from the wringer frame.

From the foregoing description it will be seen that I have provided a clothes wringer 5 with an automatic pressure roll release composed of a pair of retaining members arranged to hold a movably mounted top bar in predetermined position within the wringer frame, and to allow said top bar to 10 move a certain distance to release the pressure means, said retaining members being shifted into position to release the top bar by levers actuated by the vertical movement of one of the pressure rolls.

15 I claim:

1. A clothes wringer, comprising a frame having pressure rolls and pressure means for said rolls mounted therein, a top bar movably mounted in said frame having 20 means for adjusting said pressure means, projections carried by said top bar, movably mounted retaining members co-operating with said projections, levers mounted on said frame connected to said movably 25 mounted members, said levers having tail portions arranged in the path of travel of one of the pressure roll shafts for moving said retaining members in position to release said top bar on the separation of said 30 pressure rolls.

2. A clothes wringer, comprising a frame having pressure rolls and pressure means for said rolls mounted therein, a top bar movably mounted in said frame having 35 means for adjusting said pressure means, studs carried by the ends of said top bar, retaining members slidably mounted on the side bars of said frame co-operating with said studs for holding said 40 top bar in predetermined position within said frame, said retaining members having vertically disposed slots for limiting the upward movement of said top bar, and means actuated by the separation of the 45 pressure rolls for moving said retaining members in position to release said top bar.

3. A clothes wringer, comprising a frame having pressure rolls and pressure means for said rolls mounted therein, a movably 50 mounted member carrying means for adjusting said pressure means, slidably mounted members arranged on said frame for holding said movable members in predetermined position therein, said slidably 55 mounted members having means for limiting the upward movement of the movably mounted members, and means actuated by the separation of said pressure rolls for shifting said slidably mounted members for 60 releasing said pressure means.

4. A clothes wringer, comprising a frame having pressure rolls and pressure means for said rolls mounted therein, a top bar movably mounted in said frame having pressure screws for adjusting said pressure 65

means, studs carried by the ends of said top bar, plates slidably mounted on the side bars of said frame co-operating with said studs for holding said top bar in predetermined position within said frame, 70 angular levers pivotally mounted on the side bars of said frame slidably connected to said plates at their upper ends, said levers having their lower ends arranged in the path of travel of one of said pressure 75 roll shafts on the separation thereof for shifting said plates in position to allow said top bar to move vertically a predetermined distance therein.

5. A clothes wringer, comprising a frame 80 having pressure rolls and pressure means for said rolls mounted therein, a member movably mounted in said frame having means for adjusting said pressure means, studs carried by said member, notched plates 85 slidably mounted on the side bars for holding said movable member in predetermined position within said frame, angled levers pivotally mounted on the side bars of said frame having their upper ends slidably connected to said plates, said levers having their lower ends extending across the slots of said side bars and adapted to be oscillated upon their pivots by the separation of said pressure rolls for shifting said plates 90 transversely on the frame for allowing said movably mounted member to move a predetermined distance upwardly within said frame for releasing said pressure means.

6. A clothes wringer comprising a frame 100 having pressure rolls and pressure means for said rolls mounted therein, a movably mounted member carrying pressure screws for adjusting said pressure means, plates slidably mounted on said frame for holding 105 said movably mounted member in predetermined position therein, and means actuated by the separation of the said pressure rolls for shifting said plates for releasing said pressure means.

7. A clothes wringer, comprising a frame having pressure rolls and pressure means for said rolls mounted therein, a top bar movably mounted in said frame having pressure screws for adjusting said pressure 115 means, a stud secured in each end of said top bar, a plate mounted on the outer face of each of the side bars of said frame having a vertically disposed notch, said plates co-operating with said studs for holding said 120 top bar in predetermined position within said frame, an angular lever pivotally mounted on the side bars of said frame having its upper end connected to the movably mounted plate, said angular lever 125 having its lower portion disposed in the path of travel of one of the pressure roll shafts on the separation thereof for moving said plates transversely of said frame in order to allow said stud to move vertically 130

within the slot thereof for releasing said pressure means.

8. A clothes wringer, comprising a frame having pressure rolls and pressure means for said rolls mounted therein, a top bar movably mounted in said frame having means for adjusting said pressure means, studs carried by the ends of said top bar, pins carried by the side bars of said frame, slotted plates slidably mounted on said pins having vertically disposed notches, said plates coöperating with said studs for holding said top bar in predetermined position within said frame, angular levers pivotally mounted on the side bars of said frame having slotted upper ends slidably connected to said plates, said levers having their lower ends arranged in the path of travel of one of said pressure roll shafts on the separation of said pressure rolls for moving said plates in position to allow the studs of the top bar to move vertically within the notches of said plates for releasing said pressure means.

In testimony whereof I hereunto affix my signature.

REA P. WRIGHT.
